UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

APPARATUS FOR CASTING STEREOTYPE PLATES WITHOUT RISERS.

Application filed August 4, 1924, Serial No. 730,017. Renewed November 14, 1927.

This invention relates to a mold and associated parts for casting a stereotype plate in such a manner that it will be left in the mold without any riser attached thereto.

5 The principal objects of the invention are to provide means for shutting off the metal from the mold and forcing the surplus metal out of it, so that a curved printing plate shall result which is shorter than the matrix 10 that produces it, notwithstanding that the metal composing said plate has been poured at one of the straight sides of the mold in which it is cast.

Reference is to be had to the accompanying 15 drawings, in which

Fig. 1 is a plan of a small part of a curved stereotype plate mold and hopper for the molten metal showing a preferred form of this invention in its first stage after casting 20 with the parts in a position to cut off the metal of the riser;

Fig. 2 is a sectional view of the same on the line 2-2 of Fig. 1;

Fig. 3 is a transverse sectional view on 25 the line 3-3 of Fig. 1, and

Fig. 4 is a view similar to Fig. 3 showing the final position of the parts when the metal is entirely cut off from the mold and the casting is ready to go through its final setting operation before it is removed from the 30 mold.

It is well known that stereotype printing plates are cast with a tail or riser usually formed along one edge and necessitating trimming off after the cast is delivered. 35 This invention is designed to make a plate which is freed from its tail or riser during the casting operation, and which is shorter than the matrix from which it was cast.

40 By avoiding the presence of the riser on the plate when cast the plate can be sent to the press earlier than otherwise would be the case, because it is not necessary to wait for the riser to cool, and because the usual trimming operation which cuts off the riser is 45 eliminated.

This invention involves the use of a gate for cutting off the metal supply after a plunger located between the gate and the

cast plate has pushed back into the metal 50 supply such unnecessary metal as lies between the plate proper and the gate. This plunger enters the mold space, or rather the space ordinarily occupied by that part of the riser adjacent to the plate, and forces 55 the metal out of that space before the plate congeals.

I have shown the invention as applied to a mold having a back 10, only a fragment of which is shown but which ordinarily is of 60 substantially semi-cylindrical shape, and a cylindrical core 11 having two casting faces upon it for use alternately with the back. Those skilled in the art will understand that the cylinder or core 11 may rotate a half a 65 revolution after each casting operation to deliver the plate and that the back 10 also has a vertical reciprocating motion to free the matrix from the plate before the cylindrical core carrying the plate begins to 70 turn. The back also is provided with two opposite matrix clamps 12, only one of which is shown, each having a clip 13 projecting into the mold for engaging the edge of the 75 matrix 14.

Instead of pumping the metal directly into the mold from an ordinary pump, I prefer to provide means whereby the metal can be fed in by gravity, although this is not essential to this invention. I have shown this 80 means in the form of a hopper 15 adapted to receive molten metal from a pump if desired and to retain it in molten condition. This hopper may be of any desired kind and I will not describe it in detail except that it 85 has an outlet passage 16 under a wall 17 at its end. This wall 17 has a curvature above the passage 16 fitting the cylindrical surface of the core 11 so as to prevent the passage of metal upwardly between the two. 90 The passage 16 is located just above the matrix clip 13 and communicates with the edge of the mold cavity so that the metal may flow continuously from the hopper into the mold to fill it. As the metal congeals in the mold any shrinkage will be compensated for by the molten metal in the hopper having free access to the top of the mold. Thus 95

the hopper performs among other functions that of a riser.

For the purpose of cutting the metal off from the mold at the proper time, that is, just before the metal at that point is set, I provide a sliding gate 20 in the bottom of the hopper adapted to be projected through the passage 16 to close the same, as indicated in Fig. 4. This gate is connected with an arm 21 on a shaft 22, which shaft is connected with means for operating it at the proper time. The shaft 22 is designed to be operated once for each cast. It will be noted that this gate or valve 20 moves substantially radially with respect to the core. It is shown as having a series of grooves 23 which permit the metal of the tail or riser to escape back into the hopper when gate 20 closes.

If no other mechanism were provided this construction would leave a tail or short riser on the plate extending from the bottom edge of the matrix clip 13, that is, from the bolster of the matrix, up to the bottom of the gate 20. This tail would be as long as the width of the matrix clip plus the thickness of the bottom of the hopper 15. Such a plate would be too long to put on a printing press cylinder and would have to be machined away, which would consume time and labor.

For the purpose of eliminating this riser, I have provided a plunger 24 mounted preferably in or on the core 11 which is adapted to move into position between the lower edge of the gate 20 and the face of the matrix clip 13 so as to fill the space between the plate proper and the gate. The end of this plunger may be parallel with and fit the shape of the wall formed by the end of the matrix clip and the edge of the bottom of the hopper. It may move parallel with the gate 20 in the opposite direction and is intended to eject all metal between the edge of the plate proper and the gate 20. For the purpose of operating the plunger 24 I provide a longitudinally moving slide 25 having a tongue 27 fitting a groove or other undercut opening 26 formed in the back surface of the plunger. The tongue and groove are cut at an angle to the face of the cylinder 11. This is a small angle, as shown in Fig. 1. The slide is operated by an arm 28 which is connected with the shaft 22 and also with the main shaft of the cylinder or core 11 so that all these things are timed to operate in a definite relation to each other. This relation is preferably such that the operation to be described below can take place in the other there set forth.

It will be understood that the hopper 15 is kept filled up to a certain level with molten stereotype metal and that metal is kept in a molten condition in the hopper by any desired means. The core 11 comes to a

stop in the position shown in Fig. 3, the matrix being clamped not only at the end shown, but at the opposite end by a pair of clips similar to 13. At this time the plunger 24 may be in the position shown in Fig. 3 but the gate 20 is closed. The next step in the operation is the opening of the gate 20 which permits the metal in hopper 15 to flow into the mold by gravity and to fill it. The gate 20 thereupon assumes the position shown in Fig. 3. Such metal as is required to make good and the shrinkage of the plate is now supplied by the hopper to the plate. At this time the cam used to operate the arm 28 comes into action and begins to force the slide 25 forward. This, through its tongue 27, forces the plunger 24 slowly outwardly in a radial direction. This plunger passes into the mold cavity and slowly moves across that cavity until it abuts against the opposite surfaces as shown in Fig. 4. While it is moving it forces out the metal which it displaces. If there is any shrinkage in the plate at that time some of the metal displaced will move down to compensate for that shrinkage. The remainder will move up into the hopper and the gateway of the gate 20. The movement of this plunger may be nicely timed to coincide with the rate of cooling of the metal so that the shrinkage of the plate may be compensated for by it. In this way the plate is wholly freed of a riser or tail. As the edge of the plate may be cut off square at the edge of the type surface it is left of the shortest possible length and its pouring end need not be machined.

After the plunger 24 has separated the plate from the metal supply, the gate 20 closes, meanwhile ejecting back into the hopper the metal which filled its gateway. The metal ejected by the gate after the gate has passed the inner edge of 17 flows back into the hopper through the grooves 23.

It should be noted that the plunger 24 may be operated endwise instead of radially if desired, that is to say it may be thrust into the space between the core 11 or the clip 13 from one end of that space, and in a direction parallel with the axis of the core 11.

By this machine I am able to cast a printing plate without a riser. I perform the operation of eliminating the riser during the operation of casting and not after the casting is finished. At the same time I provide metal to supply the deficiency caused by shrinkage of the plate and leave the plate with a smooth edge located just at the type edge of the plate.

I do not wish to be limited to the movement of the plunger 26 with the gate 20 as they might move simultaneously or nearly so and, in fact, under certain conditions the order of motion can be reversed and, in fact, other modifications can be made in the op-

eration and construction by any person skilled in the art without departing from the scope of the invention as expressed in the claims. Therefore, I do not wish to be limited in these respects, but what I do claim is:—

1. The combination with a mold for a stereotype printing plate having a space at one of its edges through which metal can fill the mold, of a gate for controlling the supply of metal to the mold and means for ejecting the metal that lies between the edge of the plate proper and said gate.

2. The combination with a stereotype plate mold consisting of two parts having a space between them and means communicating with said space for introducing molten metal thereto of a movable gate adapted to shut off the supply of metal and means for displacing the metal from the space lying between the mold cavity proper and the gate-way.

3. In a machine for casting stereotype printing plates, the combination with a mold comprising two parts having at one edge a space through which metal can be introduced to fill the space between them, of a gate, a plunger mounted on one of said parts and adapted to be moved toward the opposite part at the edge of the mold cavity, and means for moving said plunger while the metal in the cavity is fluid or plastic to expel the surplus metal from that space.

4. In an apparatus for casting a curved stereotype printing plate, the combination with the mold and means for introducing metal into it, of means movable in a radial direction for forcing the metal beyond the desired edge of the plate out of the mold before the metal sets.

5. In an apparatus for casting stereotype printing plates, the combination with a concave back and a convex core having a mold space between them for a curved printing plate and provided with a passage for the entrance of molten metal thereto, of a plunger mounted on the convex core and of a width extending from the edge of the printing surface of the plate to be produced to the bottom of the metal supply and movable across said space to entirely fill it and prevent the formation of a riser or slug at that point.

6. In an apparatus for casting molten metal to form a curved stereotype printing plate, the combination with a concave back and a cylindrical core forming a mold space for a plate between them, of means mounted adjacent to the core and back for supplying metal to said space directly, of a gate at the bottom of said metal supply movable radially with respect to the core for opening and closing the supply and controlling the entrance of molten metal into the mold, and a plunger carried by the core and movable

radially with respect thereto and arranged to fill the entire space between the gate and the adjacent edge of the cast plate, whereby the movement of the plunger will prevent the formation of the riser on that edge of the plate.

7. In a mold for casting a curved stereotype printing plate, the combination with a cylindrical core having two casting surfaces and a concave back cooperating therewith, of a container for molten metal for supplying the metal to the mold located in position to deliver metal directly to the mold at one edge, a gate for closing said container to cut off the supply of metal to the mold, a plunger movable in a direction parallel to the direction of motion of the gate and adapted to be moved across the space between the printing surface of the plate to be cast and the adjacent surface of said gate, and means for operating said gate and plunger back and forth once during each half revolution of the core.

8. In a mold for casting a curved stereotype printing plate, the combination with a cylindrical core having two casting surfaces and a concave back cooperating therewith, of a container for molten metal for supplying the metal to the mold located in position to deliver metal directly to the mold at one edge, a gate for closing the bottom of said container to cut off the supply of metal to the mold, a plunger located to move in a direction parallel to the motion of the gate and adapted to be moved entirely across the space between the printing surface of the plate to be cast and the adjacent surface of said gate, and means for operating said gate and plunger back and fourth once during each half revolution of the core to first open the gate while the core is in stationary casting position, then advance the plunger through the mold cavity when the plate has been cast but the parts of it adjacent to the plunger have not become solidified and finally close the gate and start the cylinder to rotating for delivering the solid plate.

9. In a mold for casting a curved stereotype printing plate, the combination with a cylindrical core having two casting surfaces and a concave back cooperating therewith, of a container for molten metal for supplying the metal to the mold located in position to deliver metal directly to the mold at one edge, a gate for closing the bottom of said container to cut off the supply of metal to the mold, a plunger located to move in a direction parallel to the motion of the gate and adapted to be moved entirely across the space between the printing surface of the plate to be cast and the adjacent surface of said gate, and means for operating said gate and plunger back and forth once during each half revolution of the core, the means for

operating the plunger comprising a slide movable longitudinally with respect to the core and having an angular connection with the plunger.

5 10. In an apparatus for casting a curved stereotype printing plate, the combination with a mold, and means for introducing

molten metal therein, of movable means for forcing the metal while in a soft state beyond the edge of the plate that is to be cast 10 and out of the mold.

In testimony whereof I have hereunto affixed my signature.

HENRY A. WISE WOOD.
